UNITED STATES PATENT OFFICE.

SYLVESTER J. BROWN, OF DENVER, COLORADO, ASSIGNOR, BY MESNE ASSIGNMENTS, TO THE BROWN SADDLE COMPANY, OF ELYRIA, OHIO.

DESIGN FOR A BICYCLE-SADDLE SEAT.

SPECIFICATION forming part of Design No. 29,247, dated August 16, 1898.

Application filed July 27, 1896. Serial No. 600,713. Term of patent 14 years.

To all whom it may concern:

Be it known that I, SYLVESTER J. BROWN, a citizen of the United States, residing at Denver, in the county of Arapahoe and State of Colorado, have invented and produced a new and original Design for Bicycle-Saddle Seats, of which the following is a specification, reference being had to the accompanying drawings, showing the same.

10 In the drawings, Figure 1 is a plan view of a saddle-seat showing my design. Fig. 2 is a side elevation thereof. Fig. 3 is a central longitudinal sectional view, and Fig. 4 is a transverse sectional view on line 4-4 of Fig. 1.

15 The leading or material features of my design consist of a pelecoidal or pear-shaped seat having its broad rear end curved upward as a whole and having a central longitudinally-disposed lenticular depression in its top 20 surface, said top surface being curved outward and downward at and near the marginal

edges and inward and downward at and near the edges of said lenticular depression, whereby a vertical section taken in any direction from said depression to the marginal edges of 25 the seat will show a convexly-arched top surface.

Referring to the parts by letters, *a* represents the narrow horn or pommel of the seat, *b* the upwardly-curved broad rear end, and *c* 30 the lenticular depression.

Having described my invention, what I claim as new, and desire to secure by Letters Patent, is—

The design for a bicycle-saddle seat, as 35 herein shown and described.

In testimony whereof I affix my signature in presence of two witnesses.

SYLVESTER J. BROWN.
